(57) **CLAIM**

The ornamental design for a tool handle, as shown and described.

DESCRIPTION

FIG. 1 is an isometric view of a first embodiment of a tool handle incorporating our new design, wherein the dot-dash lines define the boundaries of the claimed design. The dash-dash lines depict portions of the handle that are not considered part of the claimed design.

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

1 Claim, 5 Drawing Sheets

FIG. 2

FIG. 3

FIG. 5

FIG. 4
